UNITED STATES PATENT OFFICE

ALFRED R. MORRILL, OF SWAMPSMOTT, MASSACHUSETTS, ASSIGNOR TO UNITED SHOE MACHINERY CORPORATION, OF PATERSON, NEW JERSEY, A CORPORATION OF NEW JERSEY

SEWING MACHINE

Application filed October 31, 1918, Serial No. 260,419. Renewed December 22, 1925.

The invention relates to inseam shoe sewing machines such as are used for sewing the uppers to the soles of turn shoes or the welts and uppers to the insoles of welt shoes.

5 All the features of the invention are applicable to machines in which the stitch forming and work guiding devices are constructed and actuated to impart a continuous feed to the work during the sewing and are shown embodied in such a machine, although certain of the features are also applicable to intermittent feed machines.

One feature of the invention consists in mounting the channel guide to move with 15 the needle in the line of feed. With this construction the return movement or back feed of the channel guide takes place after the needle has been retracted, and in the case of a pointed shoe the shoe may move back with 20 the channel guide as it back feeds, thus permitting the sewing of a narrower toe than could otherwise be conveniently sewed since the shoe may be swung or turned on the channel guide to properly locate the succeeding 25 stitch as the channel guide and shoe back feed. The swinging of the shoe during the back feed of the channel guide results in a forward feed to the outer or welt surface of the seam, while the inner or channel surface 30 remains substantially stationary with relation to the path of the needle. Consequently the stitches may be more accurately and conveniently distributed and a more pointed toe may be sewn than is practicable with constructions in which the channel guide is back 35 fed with relation to the needle while the needle is still in the work and prevents its backward movement with the channel guide.

Another feature of the invention consists 40 in utilizing a roll as the channel guide and so actuating the roll that during its forward travel it does not rotate and that during its return travel it rotates at a speed to continue or assist the forward feed of the shoe. With 45 this construction the roll during a part of its forward travel cooperates with the back gage or work guide to clamp and feed the work, and during the remainder of its forward travel cooperates with and assists the needle 50 in feeding the work while the back gage or

welt guide is being back fed. During its return or back feed the rotation of the roll eliminates the frictional drag which would otherwise occur and also assists the back gage or welt guide in continuing the forward feed since the work at this time is still clamped between the forwardly moving gage and the forwardly rotating roll. 55

Another feature of the invention consists in mounting the thread arm to move in the line of feed with the needle so that its relation to the needle is unaffected by the travel of the needle in the line of feed and its proper action upon the thread during the stitch forming cycle is therefore insured. 60

Another feature of the invention consists in so actuating the needle guide that it will engage and support the work against the backward pull of the needle until the barb has emerged from the work. The guide is 65 preferably pressed yieldingly against the work so that it will accommodate itself to varying thicknesses, and is locked against rearward movement until the barb of the needle emerges from the upper or from the welt, 70 after which it is withdrawn to its retracted position. With this construction the needle guide acts to press the welt and upper firmly into the shoulder of the sole and to hold them until the barb of the needle has emerged 75 from the work. The guide thus supports the work directly at the sewing point until the needle has drawn the thread through the work, and also forces the welt and upper over the barb of the needle so that the upper or 80 upper and welt are not drawn away from the shoulder in drawing the bight of the needle loop through the work. This is of especial advantage in sewing along the 85 shanks where with the usual construction of 90 needle guide the only support for the shoe against the pull of the needle may be the back rest which engages the upper or last some distance below the inseam with the resulting 95 danger that the operator may tip or rock the shoe on the channel guide out of proper relation to the needle during this part of the sewing.

The various features of the invention will 100 be readily understood from an inspection of

the accompanying drawings, and the following detailed description of the mechanism illustrated therein.

In the drawings, Figure 1 is a right hand side elevation of a machine embodying the various features of the invention in their preferred forms; Fig. 2 is a left hand side elevation of the machine; Fig. 3 is a partial front elevation, certain parts being removed to more clearly illustrate the parts behind them; Fig. 4 is a detail sectional elevation looking toward the left in Fig. 3; Fig. 5 is a sectional detail elevation looking toward the right in Fig. 3; Fig. 6 is a sectional elevation substantially on the line 6—6 of Fig. 4; Fig. 7 is a detail side elevation of the needle guide mechanism; Fig. 8 is a plan view of the parts shown in Fig. 7; and Fig. 9 is a sectional view on line 9 of Fig. 7.

In the drawings the invention is shown embodied in a welt and turn sewing machine which is similar in many respects to the machine shown and described in the Patents, No. 1,076,201, October 21, 1913, and No. 1,108,560, August 25, 1914.

The machine is provided with a curved hook needle 2, a looper 4 to thread the needle after the needle has passed through the work, a thread measuring arm 6 arranged to engage the thread on the looper side of the work between the needle and the work, a back gage 8 which, as shown, also acts as a welt guide, a take-up 10, and an auxiliary take-up 12, all of which are similar in construction to the corresponding parts in the machine of the patents. The machine may also be provided with the usual back rest which is not shown. The channel guide is in the form of a small roll 14 shaped to engage the bottom of the channel or the base of the rib on the sole, and the periphery of which is preferably toothed or notched to better grip the work. The needle, the channel guide and the back gage (welt guide) are all reciprocated in the line of feed and are timed to impart a continuous feed to the work during the sewing.

The needle and the channel guide roll are mounted on a slide 16 which is similar in construction to the feed slide of the above patents and is reciprocated by a cam lever 18 engaging a feed cam 20 on the cam shaft. The needle is secured in a needle segment which is pivotally mounted and guided in a supporting plate 22 projecting downward from the slide 16. The needle segment is connected to an actuating lever 24 by a link 26 having ball joints at its ends to permit the movement of the needle segment in the line of feed. The channel guide roll is carried on the lower end of a shaft 28 which is mounted in a bearing bracket 30 secured to the slide 16 and the upper end of the shaft is connected through gearing 32 with a worm 34 on the cam shaft. The worm prevents independent rotation of the roll and the gearing and

worm are so proportioned that they will not transmit any rotary motion to the channel roll during its forward travel but will rotate it during its backward travel at a speed sufficient to impart a forward feed to the work.

The thread arm 6 is also mounted on the supporting plate 22 to move with the needle in the line of feed so that its relation to the needle is undisturbed. The thread finger is operated through a cam lever and link as in the above patents.

The swinging arm 36 which carries the back gage (welt guide) is mounted on a supporting plate 38 secured to a rod 40 mounted to slide lengthwise in bearings in the machine frame and also forming the supporting stud on which the slide 16 is mounted. The upper end of the arm is supported on a sleeve 42 which is clamped in a bearing in the plate 38 and which surrounds and slides on a fixed stud 44. The arm is connected by a link and ball joints to a back gage slide 46 which is operated and locked at proper intervals by mechanism similar to that of the above patents. The rod 40 is reciprocated by a cam lever 48 the forward end of which is pivoted to a fixed bracket 50 and the rear end of which carries a roll engaging the feed cam 20. The lever is connected to the rod by a pivot stud 52 adjustably secured in a slot in the lever and engaging a pivot block which fits within a transverse slot in the enlarged end 54 of the rod. By adjusting the stud 52 the travel of the back gage in the line of feed may be varied in accordance with the length of stitch to be sewed and in accordance with the adjustment of the mechanism which reciprocates the needle and channel guide.

The timing of the parts is preferably as follows:

Assuming that the needle is being retracted, the needle, needle guide, channel guide roll, back gage and thread arm are all moving in the direction of the feed and the channel guide and back gage, or the channel guide, back gage and needle and the needle guide in the machine shown are engaging the work and moving it forward in the line of feed. After the needle has reached its retracted position the needle and channel guide are back fed during which movement the needle may be advanced toward the work. During the back feed of the needle and channel guide the channel guide is rotated to cooperate with the forwardly feeding back gage in continuing the feed of the work. After the back feed of the needle and channel guide has been completed and their forward movement has begun, the needle enters the work. As soon as the needle has penetrated the work the back gage is unlocked and is simultaneously moved away from the work and back fed. During the

back feed of the back gage the forward feed of the work is continued by the forward travel of the needle or needle and needle guide and channel guide. After the back gage has been back fed and its forward travel begins it is moved forward against the work and is locked as the needle is about to begin its retracting stroke. The parts all continue to move forward in the line of feed until the needle has been retracted and then the cycle is repeated.

The machine is provided with a needle guide 56 carried by the rock shaft 58 about which the needle segment oscillates. The needle guide is operated through a segment 60 secured to the end of the rock shaft and engaged by a segment 62 adjustably secured to one section 64 of a two-part actuating lever, the other section 66 of which is engaged and operated by a cam on the cam shaft. The two sections of the actuating lever are pivoted to turn about the same stud 68 and they are connected by a lug 70 on the forward end of the rear section which projects laterally into a recess in the side of the forward section. There is a limited amount of lost motion between the lug and the sides of the recess and a spring 72 tends to hold the lug in engagement with the upper side of the recess. A locking roll 74 is arranged between a surface on the forward section and the surface of a stationary segment 76 which is secured to the bearing for the pivot stud 68. The roll is forced yielding in a direction to prevent upward movement of the forward section of the lever by a spring 78 and is raised out of locking position by the lug 70 when the rear section of the lever is rocked to raise the forward section and thus retract the needle guide.

When the cam on the cam shaft operates the rear section of the actuating lever to advance the needle guide, the two sections of the lever move together until the guide engages the work, after which the rear section of the lever moves independently compressing the spring 72 so that the needle guide is pressed firmly against the work and presses the upper or welt and upper snugly against the shoulder of the sole. The yielding of the spring after the needle guide engages the work also permits the guide to accommodate itself to variations in the thickness of the materials at the sewing point. When the lug 70 moves away from the upper side of the recess in the forward section of the lever it releases the locking roll 74 so that the needle guide is locked against backward movement, and positively holds the guide against the work during the retracting stroke of the needle and until the barb of the needle has emerged from the rear side of the work. The rear section 66 of the lever is then rocked in a direction to raise the forward section 64. During the first movement of the rear section

the lug 70 lifts the locking roll 74, thus releasing the forward section of the lever, after which the lug engages the upper side of the recess and lifts the forward section to retract the needle guide. The cam for retracting the needle guide is so shaped with relation to the cam which retracts the needle that the needle guide will be retracted just after the barb of the needle emerges from the work whatever the thickness of the work at the point engaged by the guide and penetrated by the needle.

In the continuous feed machine shown, the needle guide not only presses the welt and upper over the barb of the needle as above explained, but it also co-operates with the other parts in feeding the work and relieves the needle of the strain to which it might otherwise be subjected during the back feed of the back gage. At this time, the work is clamped between the channel roll and needle guide, both of which are moving forward in the line of feed.

While it is preferred to employ the specific construction and arrangement of parts shown and described in embodying the invention in a machine having the general construction and mode of operation of the machine shown and described in the patents above referred to, it will be understood that this construction and arrangement is not essential to the broader features of the invention and may be varied or modified as found desirable or best suited to the construction and mode of operation of the machine in which it is to be embodied.

Claims:

1. A sewing machine, having, in combination, stitch forming and work guiding mechanism including a needle and a channel guide, and mechanism for reciprocating the channel guide in the line of feed timed to back feed it while the needle is withdrawn from the work.

2. A sewing machine, having, in combination, stitch forming and work guiding mechanism including a needle and a channel guide, and mechanism for reciprocating the needle and guide in the line of feed timed to back feed them while the needle is withdrawn from the work.

3. A sewing machine, having, in combination, stitch forming and work guiding mechanism including a needle, a back gage and a channel guide, and mechanism for reciprocating them in the line of feed timed to back feed the needle and channel guide during the forward feed of the back gage and to back feed the back gage during the forward feed of the needle and channel guide.

4. A sewing machine, having, in combination, two supports mounted to reciprocate in the line of feed a needle and a channel guide carried on one support, a back gage carried on the other support, and mechanism for

- reciprocating the supports timed to alternately back feed them.
5. A sewing machine, having, in combination, stitch forming and work guiding mechanism including a needle and a channel guide roll, mechanism for advancing the roll in the direction of the feed without rotation, and for returning and rotating it at a speed to continue the feed of the work during its return.
10. A sewing machine, having, in combination, stitch forming and work guiding mechanism including a needle, a back gage and a channel guide roll, mechanism for reciprocating the back gage and roll in the line of feed timed to alternately back feed them, and mechanism for rotating the roll during its back feed only.
15. A sewing machine, having, in combination, stitch forming and work guiding mechanism including a needle, back gage and a channel guide roll, and mechanism for reciprocating the back gage and roll in the line of feed timed to alternately back feed them, and mechanism for preventing rotation of the roll during its forward travel and for rotating it during its return travel to continue the forward feed of the work.
20. A sewing machine, having, in combination, stitch forming and work guiding mechanism including a needle, a back gage and a channel guide roll, mechanism for reciprocating them in the line of feed timed to back feed the back gage during the forward feed of the needle and roll and to back feed the needle and roll during the forward feed of the back gage, and mechanism for preventing rotation of the roll during its forward feed and for rotating it during its back feed to cooperate with the back gage in feeding the work.
25. A sewing machine, having, in combination, a hook needle movable in the line of feed, a looper to thread the needle after passing through the work, and a thread measuring arm moving with the needle in the line of feed arranged to engage the thread on the looper side of the work between the needle and the work.
30. A sewing machine, having, in combination, stitch forming and work guiding mechanism including a needle, a thread arm, and a channel guide, mechanism for moving the needle and thread arm in the direction of feed while the needle is in the work and in the opposite direction while the needle is withdrawn from the work, and mechanism for actuating one or more of the other work engaging devices of the stitch forming and work guiding mechanism to continue the feed while the needle is out of the work.
35. A sewing machine, having, in combination, a hook needle, a needle guide and mechanism for actuating the guide to positively support the work against the back-
ward pull of the needle and to thereafter withdraw from the work.
40. A sewing machine, having, in combination, a hook needle, a needle guide, mechanism for pressing the guide yieldingly against the work, for locking it against backward movement during the first part and for retracting it during the last part of the retracting stroke of the needle.
45. A sewing machine, having, in combination, a hook needle, a needle guide, mechanism for pressing the guide against work of varying thickness, for locking it against backward movement, and for retracting it as the needle barb emerges from the work on the backward stroke of the needle.
50. A sewing machine, having, in combination, a hook needle, a needle guide, mechanism for pressing the guide against work of varying thickness for locking it against backward movement, and for retracting the guide as the needle barb emerges from the work.
55. A sewing machine, having, in combination, a hook needle, a needle guide, a channel guide, mechanism for actuating the needle guide to clamp the work between the guides and for locking the needle guide while the needle is drawing the bight of the needle loop through the work.
60. A sewing machine, having, in combination, a hook needle, a back gage, a channel guide, mechanism for actuating the same to continuously feed the work during the sewing, a needle guide and mechanism for actuating the guide to support the work against the backward pull of the needle.
65. A sewing machine, having, in combination, a hook needle mounted to reciprocate in the line of feed a channel guide and back gage cooperating therewith to continuously feed the work, a needle guide and mechanism for actuating the guide to support the work against the backward pull of the needle.
70. A sewing machine, having, in combination, a hook needle, a needle guide, a channel guide, mechanism for reciprocating the guide yieldingly against the work, for locking it against backward movement during the first part and for retracting it during the last part of the retracting stroke of the needle.
75. A sewing machine, having, in combination, a hook needle, a needle guide, mechanism for pressing the guide against work of varying thickness, for locking it against backward movement, and for retracting the guide as the needle barb emerges from the work on the backward stroke of the needle.
80. A sewing machine, having, in combination, a hook needle, a needle guide, mechanism for pressing the guide against work of varying thickness for locking it against backward movement, and for retracting the guide as the needle barb emerges from the work.
85. A sewing machine, having, in combination, a hook needle, a needle guide, a channel guide, mechanism for actuating the needle guide to clamp the work between the guides and for locking the needle guide while the needle is drawing the bight of the needle loop through the work.
90. A sewing machine, having, in combination, a hook needle, a back gage, a channel guide, mechanism for actuating the same to continuously feed the work during the sewing, a needle guide and mechanism for actuating the guide to support the work against the backward pull of the needle.
95. A sewing machine, having, in combination, a hook needle mounted to reciprocate in the line of feed a channel guide and back gage cooperating therewith to continuously feed the work, a needle guide and mechanism for actuating the guide to support the work against the backward pull of the needle.
100. A sewing machine, having, in combination, a hook needle, a needle guide, a channel guide, mechanism for reciprocating the guide yieldingly against the work, for locking it against backward movement during the first part and for retracting it during the last part of the retracting stroke of the needle.
105. A sewing machine, having, in combination, a hook needle, a needle guide, a channel guide, mechanism for reciprocating the same to continuously feed the work during the sewing, a needle guide and mechanism for actuating the guide to support the work against the channel guide during the back feed of the back gage.
110. A sewing machine, having, in combination, a hook needle, a needle guide, a channel guide, a back gage, mechanism for actuating the same to continuously feed the work during the sewing and mechanism for actuating the needle guide to clamp the work against the channel guide during the back feed of the back gage.
115. A sewing machine, having, in combination, a hook needle, a needle guide, a channel guide, a back gage, mechanism for actuating the same to continuously feed the work during the sewing and mechanism for actuating the needle guide to clamp the work against the channel guide during the back feed of the back gage.
120. A sewing machine, having, in combination, a hook needle, a needle guide, a channel guide, a back gage, mechanism for actuating the same to continuously feed the work during the sewing and mechanism for actuating the needle guide to clamp the work against the channel guide during the back feed of the back gage.
125. A sewing machine, having, in combination, a hook needle, a needle guide, a channel guide, a back gage, mechanism for actuating the same to continuously feed the work during the sewing and mechanism for actuating the needle guide to clamp the work against the channel guide during the back feed of the back gage.

- against the channel guide during the back feed of the back gage.
20. A sewing machine having, in combination, stitch-forming and work-guiding mechanism including a needle and a channel guide roll, and mechanism for bodily reciprocating the roll in the line of feed. 70
21. A sewing machine having, in combination, stitch-forming and work-guiding mechanism including a needle and a channel guide roll, mechanism for bodily reciprocating the roll in the line of feed and for preventing rotation of the roll during its movement in the direction of the feed. 75
22. A sewing machine having, in combination, a hook needle, a looper for laying the thread in the hook of the needle, a needle guide, and means for pressing the guide yieldingly against the work and locking it against the back pull of the needle. 80
23. A sewing machine having, in combination, a hook needle, a looper for laying the thread in the hook of the needle, a needle guide, and mechanism for actuating the needle guide to engage the work and positively support it against the back pull of the needle. 85
24. A sewing machine having, in combination, a hook needle, a needle guide, an actuator connected to reciprocate the needle guide, a locking roll arranged to prevent backward movement of the guide, means for rendering the roll active and forcing the actuator in a direction to press the guide against the work and for rendering the roll inactive and retracting the actuator. 90
25. A sewing machine having, in combination, a hook needle, a needle guide, a rack engaging the guide, a locking roll for preventing guide retracting movement of the rack, means for advancing the rack and rendering the roll active upon engagement of the guide with the work and for rendering the roll inactive and retracting the rack. 95
26. A sewing machine having, in combination, a hook needle, a needle guide, a two-part reciprocating actuator, one part of which is connected to oscillate the needle guide, abutments on the parts through which motion is transmitted from the other part to retract the needle guide, a spring through which motion is transmitted from said other part to press the guide against the work, a locking roll for locking the first part against guide retracting movement, and means for rendering the roll active upon yielding of the spring, and inactive upon re-engagement of the abutments. 100
27. A sewing machine having, in combination, a hook needle, a needle guide, means for pressing the guide against the work, a locking device rendered active upon engagement of the guide with the work to prevent backward movement of the guide, and means for rendering the locking device inactive and retracting the guide. 105
28. A sewing machine having, in combination, a hook needle, a needle guide, a one way locking device arranged to prevent backward movement while allowing forward movement of the guide, means for forcing the guide against the work and rendering the locking device active and for rendering the locking device inactive and retracting the guide. 110
29. A sewing machine having, in combination, a hook needle, a needle guide, and mechanism for actuating the needle guide to engage and unyieldingly support the work against the back pull of the needle. 115
30. A sewing machine having, in combination, stitch forming and work guiding mechanism including a needle, a channel guide roll, and a back gage, and mechanism for operating these parts to impart a continuous feed movement to the work during the sewing of a seam. 120
31. A sewing machine having, in combination, stitch forming and work guiding mechanism including a needle, a channel guide, a back gage, and means for operating these parts to impart a continuous feed movement to the work during the sewing of a seam including mechanism for reciprocating the needle and guide in the line of feed timed to back feed them while the needle is withdrawn from the work. 125
32. A sewing machine having, in combination, stitch forming and work guiding mechanism including a needle, a channel guide roll, and a back gage, and mechanism including means for rotating the roll for actuating the needle, channel guide roll and back gage to impart a continuous feed movement to the work during the sewing of a seam. 130
33. A sewing machine having, in combination, stitch forming and work guiding mechanism including a needle, a channel guide, and a back gage and means for operating these parts to impart a continuous feed movement to the work during the sewing of a seam, including mechanism for reciprocating the channel guide in the line of feed timed to back feed it while the needle is withdrawn from the work. 135
34. A sewing machine having, in combination, a hook needle, a looper to thread the needle after passing through the work, a slide movable in the direction of feed in which the needle is mounted, and a thread measuring arm arranged to engage the thread on the looper side of the work between the needle and the work also mounted in said slide to move with the slide and needle in the direction of feed. 140

ALFRED R. MORRILL.
